DESIGN.

F. K. MAERZ.

LIGHTING FIXTURE.

APPLICATION FILED OCT. 25, 1918.

52,772.

Patented Dec. 17, 1918.

Inventor,
Frederick K. Maerz
By Hull, Smith, Brock & West
Atty.

UNITED STATES PATENT OFFICE.

FREDERICK K. MAERZ, OF CLEVELAND, OHIO, ASSIGNOR TO THE SCOTT-ULLMAN COMPANY, OF CLEVELAND, OHIO, A CORPORATION OF OHIO.

DESIGN FOR A LIGHTING-FIXTURE.

52,772.

Specification for Design.

Patented Dec. 17, 1918.

Application filed October 25, 1918. Serial No. 259,724. Term of patent 3½ years.

To all whom it may concern:

Be it known that I, FREDERICK K. MAERZ, a citizen of the United States, residing at Cleveland, in the county of Cuyahoga and State of Ohio, have invented a new, original, and ornamental Design for Lighting-Fixtures, of which the following is a specification, reference being had to the accompanying drawings, forming part hereof, wherein the figure is an elevation of a lighting fixture exhibiting my new design.

I claim:—

The ornamental design for a lighting fixture, as shown.

FREDERICK K. MAERZ.

Witnesses:

ROBERT L. BRUCK,
KATE N. SOMMERS.
